UNITED STATES PATENT OFFICE.

JEFFERSON V. DAVIS, OF WASHINGTON, DISTRICT OF COLUMBIA.

RAILWAY-TICKET.

1,246,064.

Specification of Letters Patent. Patented Nov. 13, 1917.

Application filed June 30, 1914. Serial No. 848,301.

To all whom it may concern:

Be it known that I, JEFFERSON V. DAVIS, a citizen of the United States, residing at Washington, in the District of Columbia, have invented new and useful Improvements in Railway - Tickets, of which the following is a specification.

My invention relates to railway tickets of that class known as "conductors' cash-fare" or "rebate" tickets, in which a part of the ticket is turned over to the passenger as a receipt for the fare paid, and another part retained by the conductor and turned in to the auditor, to serve as a record of the amount received by the conductor. The purpose of such tickets is the protection of the passenger and company against the dishonesty of conductors, but the chief objection to their use has been due to their complexity of construction, their comparatively high cost and the time and labor required in separating the ticket sections, often making it difficult for the conductor to give proper attention to cash-fare payments and to his other duties, particularly in rapid inter-urban traffic where distances between stations are short and traffic heavy. In the use of such tickets, it is the general practice to demand from the passenger an amount exceeding the fare rate, in order that a record transaction may be carried out, and to require the return of the receipt section to complete the record by compelling the passenger to turn in the receipt section at his destination point in order to secure a rebate or refund of the excess amount paid.

The primary object of my invention is to provide a ticket of the character described which is simple of construction, free from complexity, and which does not require the use of special cutters or an irregular, tedious or complicated system of division, but which may be easily and conveniently handled and expeditiously divided in order that the fare may be collected and the passenger's receipt turned over to him within a minimum period of time.

A further object of the invention is to provide a construction which secures a further reduction in the time period of manipulation by the arrangement of the matter on the ticket in such a way that the

ticket may be manipulated by either a right handed or left handed conductor with equal facility and without the necessity of an awkward adjustment of the ticket to suit the physical characteristics of the conductor in this respect.

In the accompanying drawing illustrating my invention:

Figure 1 is a front view of a cash-fare ticket embodying my invention.

Figs. 2 and 3 are fragmentary front views of the ticket illustrating ways of separating the ticket on the same line from opposite sides of the ticket.

The improved ticket embodying my invention is in the form of a strip provided at one end with an auditor's stub or section 1 and at its opposite end with a passenger's cash-fare receipt section 2, which may be printed in any way required, or as is usual in tickets of this character. These end portions 1 and 2 are connected by a body portion 3, of a width corresponding to the end portions and of any suitable length.

As shown, the body portion 3 is provided with a central column 4 and marginal or side columns 5. In said central column is a row of characters or figures designating sums of money, beginning with "0" at one end (herein that end next the receipt 2) and ending with "\$1.50" at the other end, the amounts shown herein being of constantly increased values, on a ratio or in steps of five cents difference between the respective amounts throughout. These characters or figures indicate the regular fare rates between given points or for given distances of travel, and may vary as circumstances require, the amounts shown being progressive in regular steps of five cents and simply illustrative. If the stations were spaced at such irregular distances as would not permit the fare to be collected in even multiples of five cents, the steps might be arranged on a basis of intervals of smaller amounts; or if the stations were farther apart, the steps might be larger, as will be readily understood.

In the marginal columns, which are duplicates of each other, are identical rows of figures designating sums of money of the same progressive values as in the central

column 4 and increasing by the same steps and in the same direction; that is to say, from the receipt 2 toward the stub 1, or upward in the illustration in Fig. 1. It is important to note however, that the arrangement is such that each figure in the marginal column is one step in advance of and therefore one step higher than the corresponding figure opposite to it in the central column 4. That is to say, in the illustration herewith the row begins with \$.05 in line with the "0" in the central column and ends with "\$1.50" in line with the "\$1.45" in the central column. The figures in the marginal columns 5 are designed to indicate, in connection with the figures in the columns 4, amounts paid for fare in excess of the regular fare rates. It will be observed that the like figures in the columns 5 are in transverse alinement with each other, but that, by the order of arrangement specified, the various amounts indicated in the columns 5 are each one step (here five cents) in excess of the amounts in the column 4 to which they are opposite and in connection with which they are used. For instance, the amount \$.95 in the column 4 is arranged in alinement with the amount \$1 specified in each of the columns 5. The figures contained in the column 4, with the associated higher value figures in the columns 5, are arranged in transverse sets, and the sets are respectively located on panels across the body portion of the ticket, which panels are produced by horizontal transverse weakened lines 6 extending entirely across the ticket, from edge to edge thereof. In the use of the ticket, it may be assumed that the passenger is traveling a distance for which the regular fare rate is \$.95. The conductor collects from the passenger \$.05 in excess of this amount, or \$1, and separates the ticket into two sections along the transverse weakened line between the panels bearing adjacent indications of \$.95 and \$1 in the column 4. The ticket so separated will then consist of an auditor's stub or section, whose end panel will show the amount collected (\$1) in the column 4, and a passenger's fare and receipt section whose end panel will show in each of the columns 5 the amount collected (\$1) and in the column 4 the regular amount (\$.95) of the fare. The auditor's stub or section is turned in by the conductor to the auditor in the usual way, while the passenger, on reaching his destination, presents his receipt section to the local agent and receives in return a rebate of the amount in excess above the regular fare which he has paid. In the illustration herewith, where the steps are in regular intervals of five cents, the rebate will always be that much; but in any case the rebate may be readily ascertained by noting the difference between the amount in

the central column and that in the marginal column. Also the auditor by noting this difference has a check on the local agent, and will credit him accordingly so as to refund to him the amount of rebate paid out by such agent for each passenger's receipt taken in.

An advantage arising from the construction of my improved ticket is that by providing a central row of regular fare rate indications, and opposite marginal or side rows of like figures to indicate the actual amount collected, whatever it may be, the ticket is rendered practically proof against fraud, since the two sections must tally, can not be altered after severance of the ticket to the injury of the railroad, and by the use of the duplicate side columns double security is afforded. Another advantage arising from my improved construction of ticket is that it dispenses with the cutting or severance of the strips along irregular lines, and provides for the separation of the sections by a straight tear between two cross panels, which may be easily and quickly accomplished by simply bending the ticket along the required weakened line and then manually tearing it completely and straight across in a rapid and accurate manner.

A still further advantage arising from my improved construction of ticket is that it is adapted for use with like facility by either right or left hand conductors, so that it may be manipulated with quickness and convenience and torn from either side across, obviating the necessity of the conductor turning the ticket around or disposing it in an awkward or peculiar manner to bring it into proper position for the action of the manipulating hand. This is of primary importance when the ticket is used in suburban and interurban traffic, as it enables the conductor to collect cash fares and dispense the tickets as required in a rapid and convenient manner, so that all fares may be collected within periods between arrivals at stations, which are often very close together. In this connection the improved ticket is adapted for efficient use where ordinary constructions of cash fare or rebate tickets can not be employed, on account of the amount of time required to tear and dispense the same. Furthermore, the simplicity of construction disclosed insures a high degree of economy in the use of tickets of this character over cash fare or rebate tickets of the ordinary types.

I claim:—

The herein described railway rebate ticket comprising an auditor's stub, a passenger's receipt, and an unbroken body portion integrally uniting them, said body being provided with parallel weakened lines dividing it into a series of narrow panels and inscribed on its face with a central column of figures designating sums of money

increasing in regular steps along the several panels from the receipt to the stub, and with duplicate marginal columns of the same figures increasing in the same direction but disposed on the panels respectively one step in advance of those in the central column, for the purpose set forth.

In testimony whereof I affix my signature in presence of two witnesses.

JEFFERSON V. DAVIS.
